UNITED STATES PATENT OFFICE

GEORGE H. ELLIS, OF ST. PAUL, MINNESOTA, ASSIGNOR, BY MESNE ASSIGNMENTS, TO NORTHERN INSULATING COMPANY, OF ST. PAUL, MINNESOTA, A CORPORATION OF MINNESOTA.

MACHINE FOR MAKING INSULATING FABRIC.

1,022,778.

Specification of Letters Patent.

Patented Apr. 9, 1912.

Application filed March 28, 1910. Serial No. 551,869.

To all whom it may concern:

Be it known that I, GEORGE H. ELLIS, a citizen of the United States, residing at St. Paul, in the county of Ramsey and State of Minnesota, have invented certain new and useful Improvements in Machines for Making Insulating Fabric; and I do hereby declare the following to be a full, clear, and exact description of the invention, such as 10 will enable others skilled in the art to which it appertains to make and use the same.

My invention has for its object to provide an improved machine for commercial use 15 in economically making insulating fabric or felt from flax or similar fibrous stock.

To the above ends, the invention consists of the novel devices and combinations of devices hereinafter described and defined 20 in the claims.

The improved machine is illustrated in the accompanying drawings, wherein like characters indicate like parts throughout the several views.

25 Referring to the drawings, Figure 1 is a plan view, with some parts sectioned and some parts broken away, showing the improved machine; Figs. 2^a and 2^b are supplemental views, partly in side elevation and partly in vertical section, showing the machine on a considerably larger scale than Fig. 1; Fig. 3 is a fragmentary view in side elevation, showing a portion of the lifting apron and portions of several tampers; and 35 Fig. 4 is a view in front elevation, showing a portion of the first or front tamper.

The fibrous stock to be treated is submerged in water *y* contained in a long tank 1. Secured within the tank 1, at the receiving end portion thereof, is a horizontally extended table 2, that is submerged, that is, located considerably below the surface of the water *y*. A passage 3 is left between the receiving end of the table 2 and the adjacent end of the tank, for upward return flow of the water of the tank; and this passage 3, is as shown, overlapped by an oblique stock delivering board 4 secured to said tank.

50 The stock to be treated, we will assume, to be flax which has already been reduced to a commercial form known as upholsterer's tow. So far as my present invention is concerned, this stock may be delivered onto 55 the receiving end of the table 2 in any suit-

able way, but it is preferably evenly fed in a quite finely subdivided or loose form, by an endless toothed pick-up belt 5 and co-operating toothed drums or doffers 6 and 7. The lower portion of the belt 5 runs from a supply hopper 8 and delivers the fibrous stock past the surplus rake back doffer 7 and to the feed doffer 6. The doffers 6 and 7 are shown as covered by a hood 9. As shown, the belt 5 is arranged to run over rollers 10 and 11, the shaft of the latter of which projects and is provided with a driving pulley 12. The shafts of the doffers 6 and 7 project at one side of the machine and are provided with pulleys 13 and 14.

An inclined endless lifting apron or belt extends from a point below the surface of the water *y* and below the delivery end of the table 2, to a point above the surface of the water, and the delivery end of the tank 1. This endless lifting apron is made open or with passages through which the water may freely run and, preferably, it is made up of transverse slats 15, secured to link belts or chains 16, with the said slats spaced apart to form water passages 17. The chains 16 run over sprockets 18 on shafts 19 journaled in suitable bearings on the sides of the tank 1. The upper shaft 19, which is at the delivery end of the tank, projects at one end and is provided with a sprocket 20. Under upward movements, the slats 15 of the lifting apron pass over inclined skid rails 21 secured to the sides of the tank.

The numeral 22 indicates a deflecting board located in the tank 1 below the table 2.

Working above the table 2, is a multiplicity of toothed carding cylinders or drums 23, the shafts of which are mounted in suitable bearings 24 on the sides of the tank 1 and are provided, at their projecting ends, with pulleys 25 for the obvious purpose of driving the same. The shaft bearings 24 may be secured to the tank in any suitable way but, as shown, are adjustably secured to the sides thereof by nut-equipped vertically projecting bolts 26.

The teeth of the carding cylinders 23 co-operate with fixed teeth, shown as secured to metal plates 28 set into, and forming a part of, the table 2. The teeth of the cylinders 23 and the relatively fixed teeth 27 have dull edges so that they will card but

not cut the fiber and, in fact, are constructed very much on the same plan as the teeth of a cylinder and concave of a threshing machine. Concave blocks 29 are shown as secured to the table 2 on the delivery sides of the respective cylinders. The teeth 27, it will be noted, are entirely submerged in the water, so that carding action of the stock takes place below the surface of the water.

10 This process of carding the fibrous stock, while submerged or below the surface of the water, is disclosed and broadly claimed in my earlier co-pending application, S. N. 550,360, filed of date March 19th, 1910, entitled "Process of producing insulating fabric." As more fully set forth in the said process application, the carding under the water softens and toughens the various parts of the fibrous stock, finely separates the

20 fibrous stock without cutting the same into short lengths, and breaks up the shive or woody substance of the stock. The carding action on the stock, while it is soaked and softened in the water, serves to shred and

25 form a fine beard or fuzz on the fibrous bundles, which very thoroughly intertwines and produces a fluffy firmly united but soft substance which increases the insulating efficiency of the material. Furthermore, the

30 combined carding and drawing action of the carding devices and the solvent action of the water removes the pectose or gummy substance from the fiber and makes the use of chemicals unnecessary.

35 In the arrangement of the carding devices, shown in the drawings, the fiber is only once passed to each cylinder and, hence, enough cylinders and co-operating fixed teeth should be provided to produce the proper carding

40 action by the successive operation of the several carding devices. As shown, hoods 30 are detachably placed over the cylinders 23. The last cylinder 23 delivers the carded fiber onto the submerged receiving portion

45 of the lifting apron 15; and, at this point of delivery, the fiber is preferably quite evenly distributed by hand by two persons, standing one at each side of the machine. The several cylinders 23, rotating in the direction of the arrows marked thereon, keep

50 up a continuous circulation of the water downward through the passages between the slats 15, thence along the lower portion of the receiving end of the tank and up

55 through the passages 3 again to the said cylinders. This downward travel of the water through the openings or passages in the lifting apron serves to deposit the fibrous stock on the said elevating apron;

60 and it may be here stated that the said apron, whether made of slats or otherwise, should be an open apron, that is, an apron provided with water passages through which the water may flow downward, as above stated. The flow of the water will be

more rapid through the thinnest portions of the fibrous sheet deposited on the apron, and, the more rapid the flow of the water at any particular point, the more rapid will be the deposit of fiber. Hence, there is a sort of automatic regulation of the deposit of the fiber which, in itself, has a tendency to insure a somewhat uniform thickness in the fibrous sheet.

70 The fibrous stock, after it has been deposited on the upwardly moving portion of the apron 15 and after it has been quite evenly distributed or re-arranged thereon, partly by hand and partly by the circulating water, is subjected to the action of a multiplicity of tampers. These tampers operate successively on the fibrous sheet as it is being elevated from the water, to progressively decrease the thickness and, in a reverse order, to increase the compactness 85 of the fibrous sheet. As shown, there are four of these tampers and each comprises a heavy transverse bar 31, preferably of wood, the under edges of which are beveled backward and upward in respect to the direction of the travel of the fibrous sheet 2 on the lifting apron. The ends of the said tamping bars 31 are reduced and are adjustably secured to the depending ends of crank rods 32 provided, at their upper ends, 90 with eccentric straps 33. The eccentric straps 33 work on eccentricities 34 of transverse shafts 35 mounted in suitable bearings on supporting frames 36 secured to the sides of the tank 1. The ends of the said tamping bars 31 are shown as guided for vertical movements by short vertically extended guide channels 37 on the bearing frames 36. The first tamping bar 31 is provided with a supplemental laterally spaced bar 38, spaced 105 therefrom by blocks 39 and adjustably connected thereto by nutted bolts 40 that work through slots 41 (see Figs. 3 and 4). The lower edge of the supplemental tamping bar 38 is beveled reversely to the bevel of the bar 31 to which it is secured. The tamper actuating shafts 35 are connected in pairs by sprocket chains 42 that run over sprockets thereon, and one of each of the connected shafts is provided with a pulley 43.

110 The several tampers are so set that, in the direction of the travel of the fibrous sheet, they will progressively reduce the thickness of the sheet and correspondingly increase the compactness thereof. The first 120 or double tamper 31-38, in virtue of its reversely beveled tamping bars, has a sort of a gathering action on the stock engaged between the same. The supplemental tamping bar 38 also serves as a sort of a rough 125 gage to approximately indicate when the proper amount of fibrous stock has been distributed or re-arranged upon the upwardly moving lifting apron. The other tampers 31 have a backward crowding 130

action on the fibers of the fibrous stock and the combined action thereof crowds the fiber, first, in one direction and, then, in another, and insures a thorough intertangling of the fibrous material as well as evenness and compactness in the fibrous sheet as it is gradually reduced in thickness thereby.

The fibrous sheet, after it has passed the last tamper, is preferably passed under a heavy squeezing roller 44, held with freedom for vertical and rotary movements by projections of the bearing frames 36.

From the upper delivery portion of the lifting apron, the fibrous sheet is passed between coöoperating wringing rollers 45 and 46 mounted in suitable bar pedestals 47. These wringing rollers are of the customary construction, are preferably spring-pressed together in pairs and may be driven in the usual or any suitable way.

The numeral 48 indicates a short transfer belt which runs over the lower roller 45 and over a small roller 49 mounted in suitable bearings on the delivery end of the tank 1.

What I claim is:

1. In a machine of the kind described, the combination with a water containing tank and an inclined open belt arranged to carry stock from a point below to a point above the surface of the water, a submerged table arranged to deliver the stock onto said apron, carding teeth on said table, and a toothed cylinder coöperating with said carding teeth to card the stock below the surface of the water, substantially as described.

2. In a machine of the kind described, the combination with a water containing tank, of an inclined open apron operative to carry the stock from a point below to a point above the surface of the water, and devices in the said tank for manipulating the stock in the water, including a toothed cylinder and concave which coöperates to tear

apart or card the stock below the surface of the water, and which tank is constructed to afford a continuous circuit for the water permitting the water to be circulated downward through said open apron and thence back to said manipulating devices, including said toothed cylinder and concave, substantially as described.

3. In a machine of the kind described, the combination with a water containing tank, of an inclined open apron operative to carry the stock from a point below to a point above the surface of the water, a submerged table arranged to deliver the stock onto the lower end of said apron, carding teeth on said table, and a toothed cylinder coöperating with said carding teeth to card the stock below the surface of the water, the said tank having a continuous circuit permitting the water to be circulated downward through said open apron and thence back to said beating cylinder, substantially as described.

4. In a machine of the kind described, the combination with a water containing tank, of an endless open apron operative to carry the stock from a point below to a point above the water, and a multiplicity of tampers working above said apron and operative successively on the stock to progressively reduce the thickness of the fiber sheet, the first of said tampers having laterally spaced blades with reversely beveled stock engaging lower edges, and the other tampers having stock engaging lower edges that are beveled backward in respect to the direction of the travel of the stock on said apron.

In testimony whereof I affix my signature in presence of two witnesses.

GEORGE H. ELLIS.
